UNITED STATES PATENT OFFICE.

OTTO VON MEYENBURG, OF ZURICH, SWITZERLAND.

DEVICE FOR SELECTING AND SEPARATING HEDDLES.

1,101,807.

Specification of Letters Patent. Patented June 30, 1914.

Application filed April 22, 1910. Serial No. 557,015.

To all whom it may concern:

Be it known that I, OTTO VON MEYENBURG, engineer, citizen of Switzerland, residing at Zurich, Switzerland, have invented certain new and useful Improvements in Devices for Selecting and Separating Heddles, of which the following is a specification.

This invention relates to an improvement in mechanism for selecting and separating 10 heddles. Devices of this character may be used in connection with a warp thread drawing-in machine of the type disclosed by British Patent 3707 of February 14th, 1907. Machines of this type usually include 15 as an essential feature thereof a device for successively separating the individual threads from a row of such threads, said device including a member movable against the row of threads to separate from the latter at predetermined intervals a thread 20 and properly position the same to be drawn through the heddle. A separating device of this kind forms the subject matter of my co-pending application for Letters Patent, Serial No. 557014 filed April 22nd, 1910. 25 Machines of the type above referred to also include a device for threading the warp threads into and through the heddle eyes, combined with means to hold a warp thread 30 which has been separated, in such position that it may be engaged by a hooked needle and drawn through the eye of the heddle which has been selected and separated from a series of heddles. A device of this kind 35 forms the subject matter of my co-pending application for Letters Patent Serial No. 557016 filed April 22nd, 1910, while the present application relates to mechanism for holding the selected and separated heddle in readiness for drawing a warp thread 40 separated by the first mentioned mechanism through the eye of this heddle by the second mentioned mechanism. The mechanism for selecting and separating heddles includes a fork acting as a heddle separating member, and means for reciprocating this fork and oscillating the same in a plane 45 transverse to the heddles to be separated. This general type of mechanism is disclosed

by the above mentioned British Patent 50 3707/07, and by U. S. Patent 461613.

The arrangement of parts according to the present invention is such that the ends of the fork are adapted to alternately act against the heddle shanks of the foremost 55 row of heddles and move the row of heddles away from the one selected, so that the latter is free to be engaged by the detacher and is adapted to be moved, at a suitable time, into position for threading. 60

One form of the invention is illustratively exemplified in the accompanying drawing, wherein—

Figure 1 is a front elevation; Fig. 2 a side elevation partly in section and with 65 certain parts removed; and Fig. 3 a plan.

In Fig. 2. A¹, A², A³ and A⁴ represent four heddle frames and lying on each bar thereof is a second bar B wider than the frame bar and serving to hold the heddle 70 cords apart. A frame work *a* carries four horizontal shafts *b* parallel to each other, one for each of the said heddle frames. Each shaft *b* may be driven from another shaft *w* by means of a gear wheel *c* and a 75 wheel segment *s*. At its left-hand end each shaft *b* is provided with a disk *d* having at its extreme face a suitably shaped cam. A lever *e* is provided with a roller *e*¹ which rests against this cam and a spring *f*⁵ draws 80 the lever *e* toward the disk *d*, thus causing the roller *e*¹ to move in conformity with the shape of the cam; this movement being transmitted to a shaft *f* which is capable of axial displacement in holes provided in the 85 frame-work. A suitably shaped fitting *g*¹ is provided which may move along and around the shaft *f*, and to the fitting *g*¹ a fork *g* as well as an arm *g*² are attached, the end of the latter being capable of sliding 90 in guiding grooves *i*¹, *i*², while the arms of the fork *g* are provided with projections *g*⁷, *g*⁸ directed inward (Fig. 2). Fitting *g*¹ is also provided with a slotted extension *g*³ which together with the fitting *g*¹ may move 95 axially with the shaft *f*, but which may not rotate. The movement of shaft *f* is transmitted to a gear wheel *m* by means of gear

wheel n whose diameter is one half of that of the wheel m . The latter is provided with a pin m^1 which is mounted eccentrically and which in its turn causes a swinging link o to move to and fro, so that for every complete revolution of the shaft b this link is caused to make half an oscillation. The link o is provided with two arms o^1 , which by means of spring p^1 and p^2 are connected 10 with the two ends of a beam k fitted on shaft f and carrying a pin k^1 , which projects into the slot of the extension g^3 . For every complete revolution of the shaft b the link o makes half an oscillation which 15 may be transmitted by means of springs p^1 and p^2 to the beam k . The latter however, is only rigidly connected with the fitting g^1 by the parts k^1 and g^3 as far as rotary motion is concerned. The beam k^1 can therefore 20 only follow the motion of the link when the fitting g^1 and the arm g^2 have been moved sufficiently far toward the left to allow the arm g^2 to pass the short rib i^2 , lying between the two grooves i^1 and i^2 . By 25 means of spring g^6 a constant pull toward the right is maintained on the fitting g^1 . The shaft f carries also between two collars a fitting h^1 which in turn carries the detacher h . The fitting h^1 is provided with a 30 catch h^2 which may engage with the hook-shaped lever g^4 whenever, as a result of the axial motion of shaft f , this is permitted. The lever g^4 has a right angular projection g^5 which may come into contact with a 35 collar b^1 fixed on the shaft b . The detacher h is furnished with a projection h^3 having a suitably shaped end which rests against a bushing r fitted on the shaft b . The bushing r is provided with a cam r^1 . The detacher h is kept in its normal position by 40 means of a spring h^4 . In course of rotation of shaft b the projection h^3 is forced and for a time kept aside, whereupon the detacher h moves toward the observer (Fig. 1). 45 q^1, q^2, q^3 and q^4 are hook-shaped members which serve to hold the heddles to one side after the heddle-eyes have been threaded and by means of the detacher h the threaded heddles are positioned behind the hooks of 50 these members.

The operation of the apparatus is as follows: Referring to Fig. 1 the device is made to approach the gear from left to right, as shown by the arrow. The shaft b is made 55 to revolve in the direction shown. As a result of this motion the shaft f is moved axially from left to right in a manner dependent upon the form of the cam on disk d under the action of spring f^5 . As soon as 60 this axial movement is sufficient for the catch h^2 to be caught behind the lever g^4 the shaft f is, by the same disk d , caused to return to its previous position, of which

movement the fork g partakes. The arm g^2 finally reaches a position where it may move 65 past the rib i^3 . At this instant the link o is in the position shown in Fig. 2; it has the tendency to cause the fork g to move from right to left (Fig. 2). This will take place the moment the arm g^2 passes from the 70 groove i^1 into the groove i^2 . Upon further axial displacement of shaft f , the projection g^6 strikes the collar b^1 , the lever g^4 is released and fork g is caused to return to its original position under the action of the 75 spring g^3 . The arm g^2 is now in the groove i^2 with the fork g inclined toward the left (Fig. 2) and as arm g^2 is made to move along the groove i^2 the projection g^7 of the fork g catches the heddle L^2 and forces it 80 together with the adjoining heddles toward the right (Fig. 1). The heddle L^1 is thus separated from the others. The detacher h which in its normal position is in line with the heddles, not only moves within the space 85 as defined in Fig. 1 by the two dotted positions, but as a result of the cam arrangement (r, r^1, h^3) describes at times a small circular movement around the shaft f . The effect of this compound movement of the 90 detacher h is as follows: The heddle L^1 on being isolated by the other heddles having been drawn toward the right (Fig. 1) is taken charge of by detacher h which was made to swing over toward the left (Fig. 2) 95 on the projection h^3 coming out of contact with the cam r^1 and then moves a short distance toward the left (Fig. 1) and now, due to the shape of the cam d , the shaft f and therewith the detacher h , are allowed to 100 come to a standstill for a short time in order that the selected and separated heddle may be threaded. On the axial movement of the parts f and h toward the left (Fig. 1) being resumed, the detacher h together with the 105 heddle L^1 pass the hook on the hook-shaped member q^1 where heddle L^1 is caught. The operation may be repeated for heddle L^2 . As for the first complete revolution of shaft 110 b the gear wheel m has made only half a revolution; the link o is now in the position shown by dotted lines (Fig. 2), as a result of which the fork g takes up the position shown by dash-dotted lines. Thereupon the projection g^8 forces the heddle L^3 aside, thus 115 leaving the heddle L^2 isolated. Where it is desired to arrange for two or more of these devices, where therefore the heddles have to be threaded in succession, it will be found necessary to bring the working parts into 120 motion successively. This may be done by fitting on the driving shaft w one wheel segment s for each device. These wheel segments s are displaced 90° in relation to each other on the shaft w and are so dimensioned 125 that each of them causes the respective wheel

5 *c* on the appertaining shaft *b* to make exactly one revolution. As soon as a wheel segment leaves its wheel *c* a cam *s*¹ which is also fitted on the shaft *w* enters a slot across the face of the wheel *c*, thus locking it.

After having thus described the nature of my invention, what I claim as new and for which I claim Letters Patent is:

1. In a device for the purpose specified, the combination with a heddle separating member provided with oppositely disposed projections and a depending arm, of means for reciprocating said member, a guide in which said arm is designed to travel, and means becoming operative when said member has reached the limit of reciprocatory movement in one direction to oscillate said member in a plane transverse to the heddles to be separated.
2. In a device for the purpose specified, the combination with a heddle separating member provided with oppositely disposed projections, of means for reciprocating said member, means for oscillating the same in a plane transverse to the row of heddles to be separated, and a detacher movable toward and from said separating member and adapted to engage individual heddles separated by said member from the row.
3. In a device for the purpose specified, the combination with a heddle separating member provided with heddle engaging projections, of a detacher designed to engage individual heddles separated from the row by the said member, means carried by said detacher for reciprocating said member, and means for oscillating said member in a plane transverse to the row of heddles to be separated.
4. In a device for the purpose specified, the combination with a heddle separating member having oppositely disposed projections and a depending arm, of parallel guides in which said arm is adapted to travel, means for reciprocating said member, means for oscillating the same when said depending arm has reached the end of one of said guides, and a detacher adapted to engage individual heddles separated from the row by said member.
5. In a device for the purpose specified, the combination with a heddle separating member having heddle engaging projections, of a detacher designed to engage individual heddles separated from the row by the said member, means carried by the detacher for longitudinally moving said member, means whereby said member is oscillated to separate a single heddle from the row, and means acting to oscillate said detacher.
6. In a device for the purpose specified, the combination with a heddle separating member having heddle engaging projections,

of a shaft supporting said member, means adapted to move said shaft axially, a detacher fixed to said shaft, means carried by said detacher for moving said member a limited extent along the shaft, means adapted to rock said shaft to oscillate said member when the latter has reached the limit of its movement along the shaft in one direction, and means for oscillating said detacher.

7. In a device for the purpose specified, the combination with a driven shaft, of a second shaft parallel thereto, means whereby said second shaft may be moved axially, a heddle separating member having heddle engaging projections movable longitudinally on said second shaft, a detacher fixed on said second shaft, means on said detacher for longitudinally moving said member in one direction on said second shaft, and means for returning said member to initial position.

8. In a device for the purpose specified, the combination with a driven shaft, of a second shaft parallel thereto, a heddle separating member having heddle engaging projections movable longitudinally on said second shaft, a detacher fixed on said second shaft, means carried by said detacher for moving the said member longitudinally on said second shaft, means whereby said second shaft may be moved longitudinally, and means for rocking said second shaft and oscillating said member when the latter has reached the limit of its longitudinal movement in one direction.

9. In a device for the purpose specified, the combination with a driven shaft, of a second shaft parallel thereto, a heddle separating member having heddle engaging projections movable longitudinally on said second shaft, a detacher fixed on said second shaft, means whereby said member and said detacher are moved toward and from each other and independent means for oscillating said member and said detacher, respectively.

10. In a device for the purpose specified, the combination with a driven shaft, of a second shaft parallel thereto, a heddle separating member having heddle engaging projections movable longitudinally on said second shaft, an arm depending from said member, a guide having parallel slots in which said arm is designed to travel alternately, a detacher fixed on said second shaft, means for moving said member longitudinally on the shaft until said arm has reached the end of one of said slots, and means for rocking said second shaft whereby said member is oscillated and said arm is caused to enter the other of said slots.

11. In a device for the purpose specified, the combination with a driven shaft, of a second shaft parallel thereto, a heddle sepa-

rating member having heddle engaging projections movable longitudinally on said second shaft, a detacher fixed on said second shaft, means carried by the detacher for engagement with said member, means whereby said second shaft is moved axially, and movement thereof in one direction will effect engagement of said last named means with said member, means on the driven shaft for disengaging the means on the detacher and said member when the latter has been

moved a limited distance on the second shaft, and means for oscillating said member when it has reached said limit of movement.

In testimony whereof I affix my signature in presence of two witnesses.

OTTO von MEYENBURG.
